UNITED STATES PATENT OFFICE.

GEORGE S. MORRIS, OF JACKSON, MICHIGAN.

LABELING-MACHINE.

1,344,426.

Specification of Letters Patent. Patented June 22, 1920.

Application filed May 29, 1919. Serial No. 300,719.

To all whom it may concern:

Be it known that I, GEORGE S. MORRIS, a citizen of the United States, residing at Jackson, in the county of Jackson and State 5 of Michigan, have invented a certain new and useful Improvement in Labeling-Machines, of which the following is a full, clear, and exact description, reference being had to the accompanying drawings.

10 An object of this invention is to provide a mechanism to prepare labels for application to the articles which are of such shape and size that they do not lend themselves readily to being handled by label applying 15 mechanism. In other words, this invention is to facilitate the application of labels to such articles by hand and relates particularly to a machine for preparing of the labels by applying paste thereto, and presenting the labels to an operator for application to articles being handled manually.

The methods heretofore practised for applying labels to articles of shapes not conveniently handled by a machine for the automatic application of labels, usually include the spreading of the labels over a large table and applying paste to the labels on the table by the use of a brush, and then picking up the labels by hand one at a time and applying them to the articles. This method is practised for applying labels to agricultural tools, such as hoes, rakes, forks and the like, and involved considerable waste of time in bringing the articles to a position 35 immediately adjacent the table and in reaching for the labels which must be very carefully picked up and wrapped around the handle of the fork or hoe or similar implement. A more specific object of this invention is to provide a machine for automatically taking the labels from a pile and conveying them to a position immediately adjacent to a rack or frame for holding a large number of the implements to be labeled, 40 and presenting the labels to an operator so that he may pick them up with a minimum amount of movement of the hand and without difficulty in grasping them or removing them from the surface on which they are 45 carried.

In the use of the present methods of labeling such articles it has been proven that the greatest amount of time is lost in applying the paste and in reaching for and picking up the labels. Accordingly the speed at 55 which these labels may be applied may be

very greatly increased by the use of a machine such as comprises the subject matter of this invention.

Additional objects of the invention are 60 to construct such a machine that it may be very simple, durable and capable of being cheaply manufactured and effective in operation.

I have illustrated a convenient embodiment of my invention in the drawings hereof. The method of accomplishing the above and other objects will become more apparent in the following description which relates to the drawings. The essential characteristics 70 are summarized in the claims.

In the drawings, Figure 1 is a side elevation of the machine embodying my invention; Fig. 2 is a plan of the same; Fig. 3 is an end elevation of the machine; Fig. 4 is a detail in the nature of a section of the label supporting device with parts in elevation; Fig. 5 is a side elevation of the left hand end of the machine as shown in Fig. 1, illustrating some of the parts in different positions; Fig. 6 is a sectional detail through a paste receptacle showing paste applying rollers therein.

Describing the parts by use of reference characters, the frame of the machine has 85 corner posts designated 1. Secured to the upper ends of the posts are longitudinal structural members 2. Transverse members 4 each connect and brace adjacent corner posts, while the structural members 2 are 90 connected by plate-like strips 5, 6, 7, 8 and 9, each of which have functions of carrying parts of the machine.

The lower portion of the frame is longitudinally braced by structural members 10 supported by and secured to the transverse members 4.

At 12 is indicated a broad belt running over face pulleys 14 and 15. The pulley 14 is preferably mounted on a shaft 16, supported in bearing blocks 17 and 18 fixed to the frame plate 5. The pulley 15 is shown as mounted on a shaft 20 supported in bearing blocks 21 and 22. These bearing blocks are slidably fitted to plates 24 and 25 respectively, mounted on the frame plate 9, and are connected by a cross member 26 into which is threaded a screw 27 rotatable in bearings 28 and having a hand wheel 29. Between the bearings 28 is a collar 30 rigid 110 on the screw, whereby rotation of the screw may move the bearing blocks 21 and 22 car-

rying the shaft 20 and pulley 15 longitudinally of the machine to adjust the tension of the belt 12.

The belt may be intermittently progressed so that its upper reach moves toward the left hand end of the machine by a suitable step by step mechanism. I have shown on the shaft 16 a ratchet wheel adapted to be engaged by a downwardly projecting dog 33 rigid, with the upper end of an arm 34 rotatably embracing an eccentric member 35 of a drive shaft 36. The drive shaft 36 may be constantly driven by any suitable means, which will result in rotating the pulley 14 by a step by step movement. The dog 33 preferably moves from one tooth to the next of the ratchet 33 and is urged into such engagement by a spring 38, connected with the arm 34 and the frame of the machine. The drive shaft 36 is shown as having bearings 39 mounted on the frame member 10.

Bracket arms preferably formed of heavy flat metal strips are indicated at 40 as extending over the top of the frame member 2 adjacent to the belt 12, then downwardly to support a paste receptacle 42 shown as carried on a plate 43 adapted to rest on outward extensions of the bracket arms 40. Below the bracket arms 40 are bearing brackets 44 secured thereto and carrying separated parallel shafts 45 having at their ends intermeshing gears 47. A cam arm is rigid on the shaft adjacent to each end of each shaft as indicated at 48 and 49. These arms are rounded at their outer ends as indicated in Fig. 3, and are adapted to engage the plate 43 supporting the paste receptacle to raise or lower the receptacle as the shafts are rotated. This rotation may be accomplished by means of a handle 50 on one of the shafts. Guide pins 52 are shown as carried by the plate 43 and extend downwardly through the bracket arms 40, to guide the receptacle and prevent it from lateral or longitudinal shifting while permitting its vertical movement when raised by the arms 48 and 49.

Within the receptacle 42 is a cylindrical drum 54 on a shaft 55 carried in bearings on the sides of the receptacle and having its lower surface adjacent to the bottom of the receptacle and projecting at the upper side just above the upper edge of the sides of the receptacle. The drum 54 is preferably hollow and provided with radial openings 56 in the cylindrical surface thereof. A roller indicated at 60 also has bearings in the sides of the receptacle and is shown as projecting above the top thereof and separated from the roller 54. A coöperating roller is indicated at 62 as having trunnions supported in vertically adjustable bearing members 63 threaded through nuts 64 embracing a transverse frame strip 7 which projects from the

frame a sufficient distance to provide for the bearings 63 embracing the roller 62 and allowing the roller to be the width of the belt, as are the rollers 54 and 60. The roller 62 is shown so positioned as to come between the rollers 54 and 60. The belt is arranged to travel between rollers 54 and 60 on the one side and the roller 62 on the other.

Adjacent to the pulley 14 and normally bearing against the lower reach of the belt 75 is a platen 70 carried by vertical supporting rods 72 extending through and adjustably secured to an extension of the transverse plate strip 6 by nuts 74. The labels to be applied to the articles, and which are presented by the belt 12 to the operator, are first mounted in a stack at 80 on a plate 81 formed on the upper end of a vertically reciprocating plunger 82, slidably fitted in a casing 83 carried by a supporting bracket 85 mounted on an adjacent member 10. In the lower end of the casing 83 is a plunger 85 having a lateral projection movable in a vertical slot in the casing and carrying a roller 86 while a spring 88 is interposed between the plunger 85 and the plate 81 as shown particularly in Fig. 4. The roller 86 is adapted to be acted upon by an actuating cam in the nature of a short radial arm 90, mounted on the shaft 36, whereby the plunger 85 may be moved upwardly, moving the plunger 82 and plate 81 with the labels 80 thereon, to urge them, against yielding pressure of the intervening spring, against the belt 12 at a point where it is supported 100 against deflection by the platen 70.

Surplus paste on the belt 12 may be removed by a scraper 92, preferably set to bear against the belt as it turns over the pulley 14 and arranged on an angle whereby its arcuate inner edge 94 (as shown particularly in Figs. 1 and 2) may closely fit the belt for its entire width and at the same time be presented to the belt at an angle with relation to its direction of travel. This scraper 92 is shown as secured to one end of one of the frame members 2. The paste so scraped from the belt may fall into a receptacle 96 directly beneath the scraper and carried on a supporting arm 97 projecting 115 from a corner post 1 of the frame.

The advantage of the use of this machine and manner of gaining the objects herein set out are made more clear by the following description of the operation of the 120 machine.

Assuming, for example, that the operator desires to apply labels to the handles of a large number of hoes, any suitable support in the nature of a rack or other device (not 125 shown) is provided whereby he may reach for the article with one hand and most conveniently reach the upper surface of the belt just as it turns downwardly over the pulley 14 with the other. The paste re- 130

ceptacle having been suitably filled with adhesive material of the character and consistency desired, the handle 50 is operated to raise the receptacle through the cam arms 5 48 and 49 until the rollers 54 and 60 engage the belt, as shown in Fig. 5. The roller 62 engages the upper side of the belt between these two rollers at a point between the contact points of the rollers 54 and 60 and prevents undue deflection, and allows ready 10 adjustment of the pressure of these rollers on the belt, by raising the paste receptacle through the mechanism described the desired amount. A pack or stack of the labels 15 to be used is then arranged as at 80 on the platform 81. Now the application of power to the shaft 36 actuates the arm 34 and dog 33 causing it to advance the ratchet wheel 32 and intermittently rotate the pulley 14 accordingly advancing the belt. This same 20 rotation of the shaft 36 also causes the cam arm 90 to engage the roller 86, raising the plunger and presenting the stack of labels to the under side of the belt. The surface 25 of the belt carries a small amount of paste which may be applied, to start the operation, by manually moving the belt past the paste applying rollers. The paste applying operation is automatic thereafter. The sur- 30 plus paste is scraped off by the scraper 92 and falls into the receptacle 96, leaving a comparatively thin film of paste on the surface of this belt, which is preferably of rubber or like material, at least being pro- 35 vided with a non-absorbent slightly yielding surface. This film of paste is just sufficient to cause the uppermost label, which is presented with its printed side toward the belt, to adhere thereto but is not sufficient to de- 40 face or blur the matter on the label. These labels thus secured to the belt pass over the roller 54, receiving a considerable amount of paste which covers the under surface of the label. As the operation continues labels 45 continue to be applied, and adhering to the belt, pass upwardly over the pulley 15 and forwardly along the upper reach of the belt to the operator. The intermittent move- 50 ment of the belt allows only enough time to remove the labels from the upper reach of the belt at a point nearest the operator, that is, just above the pulley 14. Thus the article to which the label is to be applied may be grasped by one hand and the label by 55 the other and quick application may be accomplished. During the interval of applying the label by hand, the belt is advanced to present the next label to him. After the label is removed the paste is then not evenly 60 distributed on the belt owing to application of paste over the area surrounding the labels as well as on the blank surface of the label. As each portion of the belt passes the scraper, however, the surplus paste is re- 65 moved and that remaining on the belt is

evenly distributed in a thin film, as described above, so that the surface of the belt is again prepared for receiving the printed side of the labels. The eccentric 35 and cam 90 are so arranged on the shaft that the 70 plunger is down while the belt is being advanced and the belt is stationary when the plunger is moved upwardly to present labels thereagainst, so that the uppermost 75 label of the stack may adhere to the belt 80 and the stack may not be otherwise disturbed by any lateral motion, such as would occur if the belt were to move while the stack were in contact therewith.

The paste receptacle is preferably shown 80 longitudinally shiftable on the plate 43, there being a stop 100 in the direction toward which it tends to move with the movement of the belt, but an additional adjustment of the rollers 54 and 60 may be had 85 with relation to the roller 62, by longitudinally shifting the paste receptacle on the plate 43, forwardly from the stop as shown in Fig. 6. The roller 60 obtains the proper pressure on the belt by slight distortion 90 from its normal course and also evenly distributes the paste thereto.

From the foregoing description, it will be seen that I have provided a machine for preparing labels for application to articles 95 and for automatically presenting them to an operator in a manner most convenient for him to reach and to pick up.

In practice two or more stacks of labels 80 may be placed upon the platform 81, thus 100 bringing a plurality of lines of labels along the belt to the operator, in case it is desired to apply two labels of different character to the same article or in case the articles are of such nature that the operator may work 105 faster with relation to the speed of the machine than with one label at a time to be presented. The invention lends itself to many adjustments and adaptations of this character, and it is found that one operator 110 may apply very many more labels, in fact several times as many labels, in a given length of time as by the hand method of applying paste to labels and picking them from a large table platform. 115

Having thus described my invention, what I claim is:

1. In a device of the character described, the combination of a traveling conveyer, means for supporting a stack of labels 120 spaced from said conveyer, means for intermittently moving said supporting means against said conveyer and for placing labels from said stack onto said conveyer one label at a time, means for applying paste to the 125 exposed surface of the labels on the conveyer, and means for progressing the conveyer to bring the labels to an operator for removal and application to an article to be labeled. 130

2. In a device of the character described, the combination of a conveyer, means for applying paste to the surface of the conveyer, means for presenting a stack of labels to the conveyer whereby the foremost label may adhere thereto, said last mentioned means being so positioned with relation to the paste applying means that the labels pass said applying means and whereby paste is applied to the exposed surface of the labels, and means for progressing the conveyer to bring the labels thereon to an operator.

3. In a device of the character described, the combination of a conveyer, means for applying paste to the surface of the conveyer, a carrier for a stack of labels, means for presenting one label at a time to the conveyer whereby its exposed surface may have paste applied thereto by said first mentioned means, and means for progressing the conveyer.

4. A device of the character described, comprising a belt conveyer, separated pulleys over which said conveyer may run, a paste receptacle, a roller for transmitting paste to the outer surface of the conveyer belt, means for advancing the belt intermittently past a discharge point, a reciprocating carrier for supporting a stack of labels between said point and the paste roller in advance of the latter, and means for reciprocating said carrier timed with relation to the belt advancing means to present the labels to the belt when it is stationary.

5. A device of the character described, comprising a belt conveyer, separated pulleys over which said conveyer may run, a paste receptacle, a roller for transmitting paste to the outer surface of the conveyer belt, means for advancing the belt intermittently, a reciprocating carrier for supporting a stack of labels, means for reciprocating said carrier, timed with relation to the belt advancing means to present the labels to the belt when it is stationary, said carrier being positioned at the forward side of said paste applying means, whereby the labels adhering to the belt pass the paste receptacle so that the exposed surface thereof receives paste.

6. In a device of the character described, the combination of a belt conveyer, a paste receptacle adjacent to the belt and having a roller for applying paste to the surface of the belt, means for presenting a stack of labels to the belt so that the label in contact with the belt adheres thereto by reason of the paste on the belt, said means being positioned in advance of the paste applying means, whereby the exposed surface of the labels may contact with the paste roller.

7. In a device of the character described, the combination of a conveyer, a paste receptacle adjacent to the conveyer and hav-

ing a roller applying paste to the surface of the conveyer, a scraper having an edge fitting the conveyer to remove surplus paste therefrom, and a reciprocating carrier for a stack of labels adapted to present the labels to the conveyer so that the label in contact with the conveyer adheres thereto by reason of the paste on the conveyer, said reciprocating carrier being positioned in advance of the paste applying means and after the scraper.

8. In a device of the character described the combination of a belt conveyer, separated pulleys over which said belt may run, a paste receptacle adjacent to the belt and having a roller applying paste to the surface of the belt, an automatically reciprocating carrier for a stack of labels adapted to present the labels to the belt, and means for advancing the belt intermittently in synchronism with said reciprocating carrier, whereby the labels are brought to an operator who may remove them before they reach said scraper.

9. A machine for applying paste to labels and for bringing the labels to an operator, including the combination of a belt conveyer, pulleys over which the belt may run, a paste receptacle, a roller for transmitting paste therefrom to the surface of the belt, means for removing surplus paste from the surface of the belt, means for rotating one of said pulleys to advance the belt intermittently, means for presenting a stack of labels to the belt while stationary so that the uppermost label may adhere thereto, said means being positioned forwardly of the paste applying means, so that the labels pass the paste applying means as the belt passes and whereby the paste is applied to the exposed surface of each label.

10. A machine for applying paste to labels and for bringing the labels to an operator, including the combination of a belt conveyer, pulleys over which the belt may run, a paste receptacle, means for transmitting paste therefrom to the surface of the belt, a scraper having an edge presented to the belt adjacent to one pulley for removing surplus paste from the surface of the belt, means for intermittently advancing the belt, and means for presenting labels to the belt in synchronism with said advancing means.

11. A machine for applying paste to labels and for bringing the labels to an operator, including the combination of a belt conveyer, pulleys over which the belt may run, a paste receptacle, a roller transmitting paste therefrom to the surface of the belt, a scraper having an edge presented to the belt adjacent one pulley for removing surplus paste from the surface of the belt, means for moving the other pulley to adjust the tension of the belt, means for advancing the

belt intermittently, and means for automatically presenting a stack of labels to the belt when stationary so that the uppermost label may adhere thereto.

5 12. In a device of the character described, the combination of a conveyer belt, means for applying paste to the belt, at the outer side thereof, means for intermittently pressing a stack of labels to the outer side of the 10 belt ahead of the paste applying means, a platen bearing against the inner side of the belt opposite the stack of labels and means for advancing the belt when the stack is out of engagement with the belt.

15 13. In a device of the character described, the combination of a pair of separated pulleys, a belt having a nonabsorbent surface and running over said pulleys, a paste receptacle having a roller for presenting 20 paste to the belt at the outer side thereof, means for intermittently pressing a stack of labels to the outer side of the belt ahead of the paste applying roller, an adjustable platen bearing against the inner side of the 25 belt opposite the stack of labels, and means in synchronism with said first mentioned means for intermittently rotating one of said pulleys to progress the belt.

14. In a device of the character described, the combination of a pair of separated pulleys, a belt having a nonabsorbent surface and running over said pulleys, a paste receptacle having a roller for presenting paste to the belt at the outer side thereof, means 30 for intermittently presenting a stack of labels to the outer side of the belt ahead of the paste applying roller, a platen bearing against the inner side of the belt opposite the stack of labels, a ratchet rigid with one 35 of the pulleys, a shaft having a dog connected therewith, engaging said ratchet for intermittently rotating the pulleys and means on said shaft for actuating the label carrying means, and means for removing 40 surplus paste from the belt ahead of the label carrying means.

15. In a device of the character described, the combination of a pair of separated pulleys, a conveyer belt running over said pulleys, a paste receptacle beneath the conveyer belt, separated rollers in the paste receptacle, one of said rollers being adapted to present 50 paste to the outer surface of the belt, a roller bearing against the inner surface of the belt between the first mentioned rollers, means for vertically adjusting said paste receptacle, means for advancing the belt, and means for presenting a stack of labels to the undersurface of the belt ahead of the 55 paste receptacle.

16. In a device of the character described, the combination of a pair of separated pulleys, a conveyer belt running over said pulleys, a paste receptacle beneath the conveyer belt, separated rollers in the paste re- 60

ceptacle, one of said rollers being adapted to present paste to the outer surface of the belt, a roller bearing against the inner surface of the belt between the first mentioned rollers, a platform on which the paste receptacle 70 may rest and be moved longitudinally of the belt, means for vertically adjusting said platform, means for advancing the belt and means for presenting a stack of labels to the under surface of the belt ahead of the paste 75 receptacle.

17. In a device of the character described, the combination of a frame, parallel shafts supported by the frame, pulleys on said shafts, a conveyer belt running over said 80 pulleys, a ratchet on one of said shafts, a dog engaging the ratchet, another shaft carried by the frame and having an eccentric for operating said dog to advance the belt intermittently, a reciprocating member for 85 carrying a stack of labels and means on the last named shaft for moving said member to present the labels to the belt when the belt is stationary, and means for applying paste to the surface of the belt and to the exposed 90 surface of the labels carried thereby.

18. In a device of the character described, the combination of a conveyer, means to advance the conveyer intermittently, a plunger for carrying a stack of labels, a spring supporting the plunger, reciprocating means engaging the spring to actuate the plunger to present the labels to the conveyer when the conveyer is stationary, and means for applying paste to the surface of the conveyer and to the exposed surface of the 95 labels carried thereby. 100

19. In a device of the character described, the combination of a frame, shafts carried thereby, a face pulley on each shaft, a belt 105 running over said pulleys, a ratchet rigid with one of said shafts, a reciprocating dog for engaging said ratchet, a plunger positioned beneath the lower reach of the belt and adapted to carry a stack of labels, constantly driven means for actuating said plunger and said dog, and paste applying means adapted to present paste over the full width of the belt as it advances whereby the exposed surface of the labels may receive 110 115 paste.

20. In a device of the character described, the combination of a frame, a shaft adjacent each end thereof, a face pulley on each shaft, a belt running over said pulleys longitudinally of the frame, a plunger positioned beneath the lower reach of the belt and adapted to carry a stack of labels, means for actuating said plunger, a scraper having a curved edge fitting the surface of the belt 120 125 where it turns over one of said pulleys and positioned at an angle with relation to the direction of movement of the belt, paste applying means adapted to present paste over the full width of the belt as it advances away 130

from the scraper and stack of labels whereby paste is applied to the surface of the belt to cause the labels to adhere thereto and whereby the exposed surface of the labels 5 may receive paste.

21. In a device of the character described, the combination of a frame, a shaft adjacent each end thereof, a face pulley on each shaft, a belt running over said pulleys, longitudinally of the frame, means for moving one of such shafts to readjust the tension of the belt, a ratchet rigid with one of said shafts, a reciprocating dog for engaging said ratchet, a plunger positioned beneath the 10 lower reach of the belt and adapted to carry a stack of labels, constantly driven means for actuating said plunger and said dog, a scraper fitting the surface of the belt where it turns over one of said pulleys, paste applying means adapted to present paste over the full width of the belt as it advances away from the scraper and stack of labels whereby paste is applied to the surface of the belt to cause the labels to adhere thereto and 15 whereby the exposed surface of the labels may receive paste, the device lending itself to the removal of the labels at any point prior to their reaching said scraper.

22. In a device of the character described, 20 the combination of a frame, shafts supported on the frame, pulleys on said shafts, a conveyer belt running over said pulleys, a ratchet on one of said shafts, a dog engaging the ratchet, another shaft carried by the 25 frame and having an eccentric arm operated by the eccentric and carrying the dog, a spring for urging the dog into engagement, a reciprocating member for carrying a stack of labels, means on the last named shaft for moving said member to present the labels to the belt, means for applying paste to the surface of the belt and to the exposed surface 30 of the labels carried thereby.

23. In a device of the character described, 35 the combination of a conveyer, a paste receptacle, a support for the paste receptacle, means for vertically adjusting said support including the parallel shafts, cam arms rigid with the shafts, gearing connecting the 40 shafts, means for manually rotating one of said shafts, means for presenting a stack of labels to the conveyer ahead of the paste applying means, and means for advancing the conveyer.

24. In a machine of the character described, 45 the combination of a conveyer, means for applying adhesive to the surface of the conveyer, means for presenting labels to the conveyer, and means for removing 50 surplus adhesive from the conveyer, the

label-presenting means coating with the conveyer between the adhesive-removing and adhesive-applying means.

25. In a machine of the character described, 55 the combination of an endless conveyer, a receptacle containing adhesive and a roller in constant engagement with the adhesive and the conveyer, means for removing surplus adhesive from the conveyer, and means for presenting labels to 60 the conveyer, the parts being cyclically arranged so that after the backs of the labels have received adhesive and they have been removed from the conveyer, the surplus adhesive is removed from the conveyer and the 65 uniform continuity of the coating of adhesive on the conveyer is restored, before presenting additional labels to the conveyer.

26. In a machine of the character described, 70 the combination of an endless conveyer, means for applying adhesive to the surface of the conveyer, a scraper for removing surplus adhesive and insuring uniform coating on the outer surface of the conveyer, and means for presenting labels to 75 the conveyer, said parts being arranged cyclically with respect to the conveyer whereby adhesive is first applied to the surface of the conveyer, the surplus removed, the faces of the labels applied in succession 80 to the conveyer, adhesive applied to their backs, and the labels brought to a position for removal, before the continuity of the adhesive coating on the conveyer is restored by the scraper preparatory to receiving additional labels.

27. The combination of a conveyer, means for applying the obverse of labels thereto, means for thereafter applying adhesive to the reverse of the labels and adjacent portions of the conveyer and means adapted to act after the label is removed for removing 90 surplus adhesive from the conveyer.

28. In combination, an intermittently moving conveyer, means synchronized with 95 the conveyer for applying the obverse of labels thereto, means for thereafter applying adhesive to the reverse of the labels and adjacent portions of the conveyer and means adapted to act after the label is removed for 100 removing surplus adhesive from the conveyer in advance of the application of a new label to that region of the conveyer.

In testimony whereof I hereunto affix my signature.

GEORGE S. MORRIS.
